UNITED STATES PATENT OFFICE.

ERNEST A. EASTMAN, OF CHICAGO, ILLINOIS, ASSIGNOR OF ONE-HALF TO CRAWFORD, McGREGOR & CANBY COMPANY, OF DAYTON, OHIO, A CORPORATION.

LAST.

No. 857,552.

Specification of Letters Patent.

Patented June 18, 1907.

Application filed November 17, 1906. Serial No. 343,875.

To all whom it may concern:

Be it known that I, ERNEST A. EASTMAN, a citizen of the United States, residing at Chicago, in the county of Cook and State of Illinois, have invented an Improvement in Lasts, of which the following description, in connection with the accompanying drawings, is a specification, like letters on the drawings representing like parts.

It is a well known fact that almost all shoes as they become worn run over on the outside to some extent, so that the foot hangs over the sole along the outside portion of the forepart of the shoe. In other words, shoes usually tread sidewise, as it is termed by last makers, so that instead of the vamp or upper remaining centrally positioned over the sole as it should, it gradually shifts or bulges outwardly along the outside of the foot, the result being that the weight of the wearer is gradually carried more and more to the outside of the shoe, thereby wearing the sole and frequently the heel unevenly.

My invention prevents this tendency of shoes by constructing the last in such a manner as to compel the shoe to throw the foot of the wearer centrally along the sole so that the foot hugs the inside of the shoe exactly as it should. The heel end of the counter is the most rigid part of the shoe, the entire counter being purposely rigid for supporting the foot and maintaining the shape of the shoe. Hence all the give or yield must come on the forepart. That is to say, the heel portion of the shoe is not only arbitrary, but it remains unalterable according to its original shape and construction. Also the heel of the foot controls the position of the foot, especially of the toe portion or forepart of the foot.

My invention takes advantage of the foregoing two facts by so constructing the heel and locating the center line of the back of the heel of the crooked last that the shoe constructed thereon has its counter portion of heel part so shaped with relation to the rest of the shoe that it positions the heel part so as to compel the forepart to tread in the center and have no tendency whatever to work over to the outside and "run over" the shoe. The back part of the counter guides or controls the rest of the shoe, as it is the only part that is absolutely rigid and hence by giving it the right shape and direction the foot quickly settles down into the heel of the

shoe in the right direction to direct or push the foot to the inside or center as distinguished from the old construction. I accomplish this result by swinging the center line of the back of the heel toward the outside of the last, and building up the outside of the heel beyond said center line, taking off the inside of the heel at the opposite side of said center line, and preferably building up the last at the inside just at the front of the heel, thereby pushing forward the outer end of the width line of the heel so that when a line is drawn from the heel to the toe through said center line at the back of the heel perpendicular to the width line, it comes at or inside of the big toe. This gives a strong tendency to the foot to move toward the inside, so that the shoe is broken in in that way and as it grows old the upper will not push over to the outside but the shoe and user get the benefit of the full tread of the sole.

In the drawings I have illustrated my invention with reference to several of the leading types of crooked lasts (as distinguished from straight lasts).

Figures 1, 2, 3 and 4 are similar bottom plan views of different forms of lasts or patterns, showing by reference to dotted lines in what respects they differ from the old construction.

My invention relates to crooked lasts, which are those commonly used at the present day, as distinguished from slipper lasts and the old fashioned "straight" lasts.

Referring to the drawings, Fig. 1 shows a swing last, *i. e.*, one form of crooked lasts, sometimes called the "walking last." The dotted curved line shows how this last has previously been constructed, and the full lines indicate my construction, from which it will be seen that the lines of the forepart *a* coincide in both constructions from the toe back to near the heel, but that the center line of the back of the heel has been shifted toward the outside from the point 1 to the point 2 and that the rear outside portion has been built up at 3 and at the opposite or inside rear end has been taken off at 4, thereby changing the width line 5 so that its outer end 6 is forward of its old position, the previous width line being indicated at 7. At and just in front of the width line the inside of the last is built up at 8 and the opposite side is taken off at 9. The result is

that the center line of the last, *i. e.*, the line which extends from the center line 2 at the back of the heel perpendicular to the width line falls on the inside of the last and extends out slightly to the inside of the toe, as shown clearly by the center line 10. The line 11 is the previous center line of the last as it has heretofore been constructed. I have similarly designated the corresponding lines and 5 last portions in each of the figures and have also drawn lines parallel to the center line of the last at a distance therefrom corresponding to half of the length of the width line. By my new construction the outside line 12 15 passes toward the toe just at the outside thereof, and the inside line, if drawn, would not touch the last, but would pass entirely to the inside thereof, whereas in the old construction just the opposite is the case, and 20 only the inside line appears, as indicated at 13, excepting in a very extreme style, where the outside line 14 just touches the extreme outside of the forepart.

From the above explanation it will be understood that my invention relates to a last in which the toe has an inward swing toward the inside of the last or foot, and resides in shifting to the outside the true center line of the back of the heel and correspondingly 25 changing the contour of the outside and inside of the heel so that the point 2 will in fact be the true center line, *i. e.*, will come at the rear center of the curvatures at either side. The result is that in use the stiff arbitrary 30 counter of the shoe is so shaped and positioned, corresponding to the last, that it compels the foot to rest properly in the shoe. Accordingly no running over of the shoe can take place, the sole is obliged to wear uniformly throughout the entire width of the 35 tread and the wearer has comfort as the joints of his foot are not pressed against the sides of the shoe in an unnatural manner.

The "width line" is defined as that transverse line which intersects the widest part of the heel at corresponding distances from the back end of the heel along the opposite identical side-curves at the sides of the heel, and it is found by folding exactly together the 40 opposite rear side edges of a paper heel-pat-

tern and striking a line at a right angle from the fold or middle crease to the widest point of said coinciding side-curves from the back end of the heel. The "center line" of the last corresponds to said fold or crease, and the "center line" of the heel is the vertical line on the heel of the last which intersects the rear end of said fold or crease. 55

Having described my invention, what I claim as new and desire to secure by Letters Patent, is,

1. A crooked last for boots and shoes, having the center line at the back of the heel located toward the outside of the last sufficiently to bring the center line of the last, 60 which extends from said center line of the heel, perpendicular to the width line, at or inside the toe of the last while yet maintaining the crooked formation of the last as distinguished from a straight last. 70

2. A crooked last for boots and shoes, having the outside rear end of the heel built up and the inside rear end of the heel taken off, so as to render the crooked last abnormal but not straight and to bring the center line at 75 the rear of the heel toward the outside sufficiently to swing the center line of the last nearer to the inside of the forepart than it is to the outside.

3. A crooked last for boots and shoes in 80 which the toe has an inward swing, having its heel so shaped that the center line passing through the middle of the width line, and a line parallel thereto intersecting the outside end of said width line embrace the toe of the 85 last between their forward ends.

4. A crooked last for boots and shoes in which the toe has an inward swing, having its heel so shaped that a line from the inside end of the width line projected forward parallel to the center line of the last falls outside 90 of the inside surface of the forepart of the last.

In testimony whereof, I have signed my name to this specification, in the presence of 95 two subscribing witnesses.

ERNEST A. EASTMAN.
